CORSAGE PIN

Blanche E. Robinson, Chicago, Ill.

Application October 15, 1948, Serial No. 54,759

2 Claims. (Cl. 24—6)

1. This invention relates generally to pins and more particularly to an improved corsage pin intended primarily for attaching flowers to the clothing.

When a florist sells a corsage it is customary to include a long straight pin for the purpose of attaching the flowers to the clothing. Such pins are usually inserted through the clothing and the wrapped flower stems along a horizontal line so that the corsage is suspended from the middle of the pin. This arrangement is not wholly satisfactory for several reasons. In the first place the flowers when so pinned are often not securely supported and are likely to become detached, and long straight pins tend to wrinkle or tear the clothing. Another disadvantage of the straight pins arises from the fact that the wearer is quite likely to stick herself accidentally with the pin attaching the corsage or while wearing it.

One object of this invention is to provide a corsage pin which will firmly support the corsage in any desired position and which may be quickly attached to both the corsage and the clothing.

Another object is to provide a pin which will not cause wrinkling or tearing of the clothing, the pin exerting a clamping action on the material rather than a pull on the sides of the holes through which it passes.

Another object is to provide a pin which makes a single opening through the clothing rather than a plurality and which is so shaped as to make it unlikely that the wearer will accidentally stick herself.

A further object is to provide an inexpensive easily constructed pin which may be quickly attached to the corsage at the time it is made by the florist and which may be readily detached therefrom and attached in any desired position by the wearer.

A further object is to provide a pin which may be used to attach flowers to the hair as well as to the clothing so that it is not necessary for the florist to know at the time the corsage is made how it is to be worn.

A further object is to provide a pin which may be supported by the material of the wearer's dress and also the shoulder strap of an undergarment for firmer support, the pin normally lying in a vertical plane parallel to the shoulder strap when a corsage is worn at the shoulder.

Other objects and advantages of this invention will of course present themselves to those familiar with the art on reading the following

2. specification in conjunction with the drawings and the appended claims.

In the drawings:

Fig. 1 is a view showing a person wearing a corsage supported by the pin of this invention;

Fig. 2 is a view partially in section showing one manner in which the pin is used;

Fig. 3 is an enlarged plan view of the pin;

Fig. 4 is a side view of the pin;

Fig. 5 is a top view; and

Fig. 6 is a side view showing the pin in the position ready for attachment to the corsage.

The preferred embodiment of the pin 10 of this invention is shown in Figs. 3—6. The pin 10

comprises a single piece of resilient wire 11 which is bent to the shape shown. Each end of the wire 11 is sharpened to provide a pair of identical points 12 and 13. The two end portions of the wire 11 are bent backwardly so as to lie parallel to the middle portion or shank 14, an enlarged loop 15 being provided at each end.

The pointed ends 12 and 13 are bent so as to curve around the loops 15 the radius of curvature of the loops 15 being slightly less than that of the curved points 12 and 13 so that the two touch in point contact in the manner shown. By this arrangement the points 12 and 13 do not project so as to be likely to stick into wearer's body and yet may be readily inserted into the wrapping material 16 of the corsage 17 and the clothing 18. Were the ends of the pin curved so that the points 12 and 13 lay in contact with the loops 15 it would be quite difficult to attach the pin to the dress material 18,

for the side portion 21 would have to be pulled away from the shank 14, assuming the position shown in Fig. 6 before the point 13 could be inserted in the dress material 18. By making the curvature of the points 12 and 13 less than that of the loops 15 the tip of the pointed end 13 is spaced slightly from the loop 15, and the pin 10 may be attached to the clothing 18 by merely inserting the point 13 into the material 18 and moving the pin parallel to the material

while guiding the material into the diverging space between the curved point 13 and loop 15 until it comes to rest in the position shown in Fig. 2. In some instances, however, it is preferred to spread the side portions 20 and 21 first and then to insert the pin to the material 18 so as to accomplish deeper penetration, but this is difficult to do when the corsage 17 is bulky and the dress material 18 is light weight.

In Fig. 2 the manner in which the pin 10 is used to support a conventional corsage 17 is

shown. The corsage illustrated consists of a single flower 22 in order to simplify the drawing. The corsage 17 is formed by wrapping a gummed tape 16 of paper or plastic about the stem 23 of the flower 22 to cover it and give it body, several layers of tape being preferably provided. When corsages having more than one flower are to be formed the procedure is usually the same except that the individual stems are first wrapped with tape and then the wrapped stems are bundled together and covered with one or more outer layers of tape 23. Insofar as this invention is concerned, however, the number of flowers is not important for the pin may be used to support any conventional type of corsage.

The preferred method of using the pin in this invention is as follows: The florist first forms the corsage 17 in the conventional manner wrapping the stem 23 with the tape 16, ribbons or other decorative material being added, if desired. The pin 10 is then spread to the position shown in Fig. 6 and held by the fingers as indicated in broken lines. The point 12 is inserted into the tape 16 and moved upwardly until in the position shown in Fig. 2. It will be noted that the full length of the side portion 20 is enclosed in the wrapping material 16.

When in this position the resilience of the wire 11, particularly that of the enlarged loop 15, causes the side portion 20 and point 12 to exert an inward force compressing the tape 16 lying between the side portion 20 and the shank 14. This force also causes the tape 16 to be tightly clamped between the point 12 and the upper loop 15. Thus the corsage 17 is firmly gripped by the pin 10 rather than merely suspended therefrom as would be the case if the resilience of the wire 11 were not brought into play. Furthermore, the space within the lower loop 15 permits the tape 16 to bunch up or wrinkle without tearing and the bunched tape tends to hold the pin in position.

The corsage 17 is now in position for attachment to the clothing 18 and may be attached by merely inserting the point 13 through the material 18 and moving the corsage 17 downwardly until the side portion 12 is completely received within the clothing 18 while guiding the material 18 between the diverging point 13 and loop 15. As stated previously, the side portion 21 may be bent away from the shank 14 prior to insertion for deeper penetration but this is not necessary because of the shape of the point 13.

A gripping action between the side portion 21 and the shank 14 and the lower loop 15 and point 13 occurs which is similar to that described in connection with the attachment of the pin 10 to the corsage 17. But in this case the clamping action is even more important because the material 18 is usually thinner than the layers of tape 16 and the pin 10 must be secure so as not to rotate in the hole 25. Furthermore, the weight of the corsage 17 must not be suspended from the hole 25. The coaction between the lower loop 15 and the curved point 13 accomplishes this support, for the dress material 18 is securely clamped between the point 13 and the loop 15 not only bearing the weight of the corsage 17 but also preventing rotation thereof. This effect would not be nearly so pronounced if the side of the loop 15 did not project beyond the shank 14 to concentrate the resilient force at that point most remote from the upper loop 15.

In order to remove the pin 10 from the cloth-

ing all the wearer needs to do is to grasp the corsage 20 and pull it upwardly. Since the clamping effect of the half of the pin received in the corsage 17 is usually greater than that of the half in the material 18, the pin moves upwardly with the corsage coming out of the dress material 18 the portion 21 being drawn through the hole 25. The gentle curvature of the end loop 15 and point 18 is such that the pin 10 is readily withdrawable the material 18 being guided between the loop 15 and the pin point 13 without bunching and the side portion moving through the hole 25.

In the event that the wearer of the corsage desires to relocate the pin in the corsage as, for example, would be the case where she desired to wear the flower upside down it is a simple matter to pull the pin out of the corsage and reinsert it in any desired position.

Another advantage of the pin of this invention arises from the fact that it lies parallel to the stems 23 of the flowers when inserted in the corsage. This fact makes it possible to insert a pin through the dress material 18 and also through the shoulder strap 26 of an undergarment 27 as shown in Figs. 1 and 2. This may not be conveniently done when a conventional straight pin is employed as the pin must be placed perpendicular to the shoulder strap 26 in order to properly support the flower 22. The pinning of the corsage to the shoulder strap 26 is particularly advantageous if the dress is made of light weight material such as rayon or silk. When this is done the weight of the corsage is suspended on the heavier undergarment strap 26 without pulling or tearing the dress. The enlarged upper loop 15 permits the dress material to bunch up slightly, as indicated at 28, which further minimizes the likelihood of tearing. Furthermore this bunching of the material 18 within the loop 15, whether the pin 10 is supported on the shoulder strap or merely on the dress material, tends to hold the pin in the inserted position augmenting the clamping action of the curved point 13 and the loop 15.

The pin of this invention may be also used to attach the corsage 17 to the hair. When this is done the pin 10 is inserted in the corsage in the same manner as when the corsage is to be worn attached to the clothing. To attach the corsage to the hair the wearer merely spreads the side portion 21 away from the shank 14 and inserts it over the lock of hair in the same manner as a bobby pin or hair pin is inserted. The curvature of the point 13 prevents the wearer from sticking the scalp with it and the clamping effect of the side portion 21, due to the resilience of the wire 11, holds the pin securely in the hair. Thus, the corsage may be worn either on the dress or in the hair and may be shifted from one location to the other without the necessity of using a number of different pins; and the florist does not need to know at the time he makes the corsage where it is to be worn.

The preferred embodiment of the pin illustrated is symmetrical, the portion insertable in the corsage being similar to the portion insertable in the clothing. This form of construction is preferred for then it is impossible to use the pin backwards. However, in some instances it has proved desirable to provide pins which are not symmetrical. For example, the side portion 20 may be made longer than the remainder of the pin to provide additional stiffening for the flower stem, or the side portion 21 may be given an

undulating shape similar to a hairpin in order to better grasp the hair when the pin is used to support the corsage on the head.

From the foregoing it will be seen that a superior corsage pin has been provided which may be quickly attached to the corsage and the clothing and which, when so attached, is securely supported without danger of bunching or tearing of the clothing. Various changes or modifications of this invention such as may present themselves to those familiar with the art may be made without departing from the spirit of this invention which is commensurate with the following claims:

What is claimed is:

1. In a corsage pin formed from a single length of resilient wire the combination including a central portion, two side portions, a connecting rounded enlarged loop joining each side portion to the central portion, and a point on the end of each of said side portions, each of the side portions being curved adjacent to the point in the same direction as the adjacent loop and normally touching the outside edge of same at a place slightly spaced from said point. 15

2. In a pin formed from a single length of resilient wire the combination including a shank 20

10

portion, two side portions, a connected rounded loop joining each side portion to the shank portion, and a point on the end of each of said side portions, each of said points being curved in the same direction as the adjacent loop and loops normally contacting the side portions near said points, the side portions exerting an inward pressure against said loops.
